FLUID PRESSURE ACTUATED SWITCH

Arthur C. Kelle, Stoughton, Mass., assignor to
Allis-Chalmers Manufacturing Company, Milwaukee, Wis., a corporation of Delaware

Application February 15, 1949, Serial No. 76,556

7 Claims. (Cl. 200—81.4)

1

This invention relates in general to a pneumatic control system and particularly to an improved control system and parts thereof suitable for operating a gas blast circuit breaker. As the currents to be interrupted by circuit breakers of the gas blast type become increasingly greater and as it becomes desirable both to operate such circuit breakers in shorter times and to encase the circuit breakers in small metal housings, the slower operating systems and the conventional arrangement of elements in the prior art circuit breakers cannot meet the desired time and space requirements.

It is therefore an object of the present invention to provide a pneumatic operating system for a gas blast circuit breaker that will perform its cycle of opening and closing operations in a minimum of time.

It is also an object of the present invention to provide an arrangement of gas blast circuit breaker elements in a metal-clad housing such that only a small housing space is necessary, while maintaining adequate insulation distances and electrical safety provisions.

It is also an object of the present invention to provide a new and improved gas blast circuit breaker in which isolating disconnect contacts are closed and maintained closed against the action of gravity and are opened in cooperation with the action of gravity.

Objects and advantages other than those above set forth will be apparent from the following description when read in connection with the accompanying drawing in which the single figure is a diagrammatic representation of a gas blast circuit breaker operating system embodying the present invention.

In the drawing, an electric circuit (not shown) connected to conductors 30 and 31 is shown as controlled by a circuit breaker of the gas blast type. The conductors 30 and 31 extend through studs 9 to contact blocks 40 which have thereon fixed contacts 3 shown as bridged by a conducting movable main or bridging contact 4. The contacts 3, 4 are contacts of high current carrying capacity and are positioned where heat can easily be dissipated therefrom and are arranged in a magnetic loop such that current flow tends to hold the contacts closed.

In parallel with the bridging contacts 3, 4 are arcing contacts 7, 8 and disconnect contacts 5, 6 connected in series. Arcing contact 8 is in permanent conductive connection with conductor or terminal element 31 and arcing contact 7 is in permanent conductive connection with a fixed me-

2

tallic chamber defining means, such as structure 41, which is arranged in spaced relationship to conductor or terminal element 30. Structure 41 substantially encloses arcing contacts 7 and 8 and is arranged parallel to terminal elements 30 and 31. The disconnecting switch, comprising disconnect contacts 5 and 6, is arranged substantially on one side of the axis of metal structure 41. Movable disconnect contact 5 is in permanent conductive connection with structure 41 and is arranged transversely to the terminal elements 30 and 31 so as to extend across the space between structure 41 and terminal element 30. The connection of terminal element 31, arcing contacts 7 and 8, disconnect contacts 5 and 6 and terminal element 30 in series defines a loop-shaped current path.

A reservoir containing gas suitable for arc extinguishing is shown at 10 and for purposes of illustration the gas therein will be considered to be air maintained under pressure of the order of 100 to 500 pounds per square inch. Reservoir 10 is arranged outside of the loop-shaped current path formed by the series connection of the arcing disconnect contacts and on the side of the axis of the metal structure 41 opposite to the disconnect contacts 5 and 6. In general, the flow of air is from the tank 10, through a blast valve 11 and a manifold 45 to the arcing contact chamber 26. Air travel continues from the arcing contact chamber 26 through the fixed arcing contact 7 into a gas cooling device or muffler 12 and through an exhaust pipe 13 to atmosphere.

Separate means such as fluid motors 42, 51, 52 and 53 are utilized to operate the arcing contacts, disconnect contacts, the bridging contacts and the blast valve, respectively. Motor 51 is provided with a piston 20 having rod 21 movable therewith and connected through linkage including a cam member 22 and a link 62 to the movable disconnect contact 5. Motor 52 has a piston 16 having a rod 17 connected through linkage to the movable bridging member 4. The cam member 18, operably connected to the rod 17, cooperates with cam 22 to prevent opening of the disconnect contact 5 unless the bridging contact 4 is in open position. Also, a camming action of cam 18 closes the disconnect contact 5, if open, upon movement of the bridging contact 4 to closed position.

Thus, motors 51 and 52, through the movement of cams 18 and 22, cooperate to actuate the movable disconnect contact 5 in contact closing direction against the action of gravity and maintain the movable disconnect contact 5 in

engagement with the fixed disconnect contact 6 against the action of gravity. Cam 22 and link 62 act as an over center toggle in that respect. To separate the cooperating disconnect contacts, the movable disconnect contact 5 is actuated by motor 51 in cooperation with the action of gravity to a lower level away from the fixed or stationary disconnect contact 6. Motor 42 is arranged substantially coaxially with respect to structure 41.

In the circuit breaker as shown in the drawing, the contacts are all shown in the closed position and current flow is from conductor 30 through contacts 3, 4 to conductor 31. Operation of solenoid valve 14 initiates the opening operation of the circuit breaker. Air under pressure from tank 10 is supplied through pipe 75, through the solenoid valve 14, through the pipe 76 to slide valve 72. With the slide valve 72 in the position shown, air passes through the slide valve, through pipe 84 to the chamber 68 of the fluid motor 52.

As pressure rises in chamber 68, valve 70 is operated admitting air to the underside of piston 16. Movement of piston 16 upward causes piston rod 17 to move the linkage to break toggle 85 to the left as viewed in the drawing, thereby opening bridging contact 4. This movement of rod 17 upward rotates the cam 18 in a counterclockwise direction and clears the path of movement of the cam 22.

Upon movement of the piston 16 upward a predetermined distance, slide valve 72, connected to move with rod 17, closes off pipe 84 from supply pipe 76 and opens pipe 76 to pipe 46. With pipe 46 supplied with air under pressure, the blast valve motor 53 is operated. Air is supplied under piston 44 and, as outlet port 48 is covered by slide valve 49, the piston 44 is moved upward opening blast valve 11. Movement of piston 44 at the top of the stroke is arrested and the shock absorbed by resilient material 90.

Opening of the blast valve 11 admits air to manifold 45 and thereby to the arcing contact chamber 26 and to the cylinder containing arcing contact operating piston 42. Movement of the piston 42 upward opens the arcing contact 8, allowing the air to blast through orifice contact 7. An auxiliary electrode 86 may be provided and connected to a resistance (not shown) which may be wound on the cooling chamber 12, which resistance is connected to contact block 40 by conductor 43. The arc gases are cooled in the muffler 12 and exhausted through pipe 13 to atmosphere.

When air is supplied to the manifold 45 by opening of the main blast valve 11, pressure air is supplied through pipe 78 to the chamber 58 of fluid motor 51. In order to assure a proper sequence of operation of arcing contact 8 and disconnecting contact 5, a needle valve 79 in the line 78 is provided for adjustment of the air flow therein. As pressure builds up in chamber 58, the valve 60 is opened admitting air under pressure to the bottom of piston 20. Movement of piston 20 and piston rod 21 upward rotates the cam member 22 in a clockwise direction about its pivot 87 opening the movable disconnect contact 5.

At a predetermined opening of the disconnect contact 5, links 50 move a slide valve 49 to uncover an exhaust port 48 and open an inlet port 47. This releases pressure beneath piston 44 and allows tank pressure to be applied on the top of the piston, thus rapidly reclosing valve 11. Upon closing of valve 11, pressure air is shut off from

chamber 26, permitting arcing contact 8 to reclose under bias of a spring (not shown). Rapid reclosing of blast valve 11 and arcing contact 8 is very necessary from the standpoints of time of circuit breaker reclosing and of air conservation.

Fluid motors 51, 52 and 53 are designed to permit a fast reclosing of the circuit breaker. Motor 51 is provided with a dumping valve 28 providing for release of pressure underneath piston 20 at or near the end of the upward stroke. An operating member 55 on rod 21 operates poppet valve 54 permitting pressure in the chamber 58 to leak off to atmosphere. The difference of pressures under the piston 20 and in chamber 58 forces the valve 28 downward against the pressure of its biasing spring, thereby opening the space underneath the piston 20 to atmosphere and immediately relieving the pressure therein.

In the motor 52 a similar action takes place, 20 poppet valve 64 is operated by operating member 65 movable with the piston rod 17. Operation of valve 64 lowers the pressure in chamber 68 thereby operating dumping valve 88 to permit a rapid release of pressure under piston 16. Motors 51 25 and 52 are therefore ready for immediate reversal.

Due to the improved fluid motors and to the rapid interruption of the circuit, the foregoing operation is completed in a few cycles. The circuit breaker is ready for reclosing which may be effected by energization of the solenoid valve 15. With solenoid valve 14 closed, pressure air from the pipe 75 is supplied through solenoid valve 15 and pipe 77 to chambers 59 and 69 of motors 35 51 and 52. With downward movement of pistons 20 and 16 the bridging contacts 4, 3 and the disconnect contacts 5, 6 are reclosed, with the limitation provided by cams 18 and 22 that the bridging contacts 3, 4 must be reclosed subsequent 40 to closure of disconnect contacts 5, 6. If movement of contacts 3, 4 tends to be faster than movement of contacts 5, 6, movement of cam 18 in a clockwise direction forces cam 22 to close contact 5. This prevents arcing at the bridging 45 contacts 3, 4 and provides for closing of the circuit at the disconnect contacts 5, 6 especially designed for closing against heavy currents.

Upon movement of pistons 20 and 16 downward, operating members 57 and 67 operate poppet valves 56 and 66 to provide release of pressure above the pistons 20 and 16 in a manner similar to the pressure release afforded by valves 54 and 64. Movement of piston rod 17 downward moves slide valve 72 to the position shown 55 in the drawing and the blast valve having been closed, the circuit breaker is immediately ready for a subsequent opening operation. Considerable saving in reclosing time is effected by the simultaneous energization of motors 51 and 52 60 for closing and by insuring of the proper closing sequence by the abutting cam members 18 and 22. The interlock afforded by cams 18 and 22 involves no loss of time.

In order to arrange the elements of a gas blast 65 circuit breaker as shown, so that it may be enclosed in a metal housing as small or smaller than the housing now utilized for an oil circuit breaker of equivalent current rating, many problems were solved. It is generally desirable in a vertical lift 70 switchgear to have the studs 9 enter the housing through the top of the breaker so that they may connect to overhead circuit connections.

The circuit breaker is enclosed in a housing 36 and is movable horizontally on wheels into a 75 cell. The entire circuit breaker and housing

is moved vertically from the floor 37 to a position in which conductors 30 and 31 are connected to the circuit to be controlled. The circuit breaker housing 36 shown at the left is the back of the circuit breaker and hence the first to enter into the cell. To illustrate the need for electrical clearances and electrical safety, the circuit breaker may be considered to be divided into two portions. All parts that may be at high potential are in the rear portion and these include the studs 9 and all of the contacts. The front portion contains only elements that are either at ground potential or that present an outer surface of insulating material thus making the front of the circuit breaker electrically dead and therefore safer for the operator. The disconnecting contacts 5, 6 are so arranged that if upon a faulty operation an arc is drawn, such arc will be blown onto the adjacent grounded housing 36.

The circuit breaker cannot be moved into the cell far enough to be raised to circuit connected position shown unless the disconnect contact 5 is in open position. This is assured by provision of stop 24 on the cell framework which stop cooperates with a link 23 connected to the cam linkage 22, whereby movement of the circuit breaker to the left forces cam 22 to rotate in a clockwise direction opening the contact 5 providing bridging contact 4 is also open. If the contact 4 is not open, cam 18 prevents movement of cam 22, and the breaker cannot be moved into the proper position for raising into the position shown. When the breaker is in the open position, the circuit breaker is then lifted to circuit connected position by a lifting means (not shown). When the circuit breaker is lifted to circuit connected position, member 23 may move into a slot 25, thereby permitting closing operation of the circuit breaker. A slot 35 in a locking member 34, operated by the circuit breaker lifting and lowering mechanism, prevents lowering of the circuit breaker unless in open position. A slot 33 permits link 89 to be in the slot 35 or on the top of member 34 if the slot 35 is not in alignment with link 89. The link 89 is lifted clear of member 34 if the disconnect is in open position.

Although the various elements of the circuit breaker system have been described as operating in conjunction with each other, the improvements disclosed have utility other than with all of the elements shown and described. For example, the fluid motors 51 and 52 may be utilized for any purpose where quick reversal of a fluid motor is desirable. While the disclosed arrangement of bridging contacts 3, 4 is desirable for circuit breakers of high current rating, these contacts may be omitted in the lower current ratings.

The improvements utilized in effecting a quick reclosure of the blast valve 11, although shown as initiated by movement of the disconnect contact 5, may as well be effected by an isolating movement of the arcing contacts 7, 8 in cases where no separate disconnect is utilized. The present disclosure of an interrupting operation utilizing an auxiliary electrode 86 and associated resistor is by way of illustration, for in the lower current ratings, these elements may be omitted.

For simplicity and clarity of disclosure, a single pole circuit breaker has been described and shown, although usually a multipole circuit breaker is operated. In such cases, the manifold 45 extends to the interrupting cham-

bers of the additional poles, and the linkages operated by motors 51 and 52 operate shafts for additionally operating the disconnect and bridging contacts of the other poles.

Although a single embodiment has been illustrated and described, it will be apparent to those skilled in the art that various changes and modifications may be made therein without departing from the spirit of the invention or from the scope of the appended claims. Features disclosed but not claimed herein are claimed in copending application Serial No. 545,929, filed July 21, 1944, and United States Patent No. 2,464,237, granted March 15, 1949, of Arthur C. Kelle.

It is claimed and desired to secure by Letters Patent:

1. In a fluid blast circuit breaker the combination of a first fixed terminal element, a second fixed terminal element, a stationary arcing contact, a cooperating movable arcing contact, means for establishing a blast of fluid under pressure adjacent said arcing contacts, a first fluid operated motor for separating said arcing contacts, means for permanently conductively connecting one of said arcing contacts with said first terminal element, a fixed metal structure in permanent conductive connection with the other of said arcing contacts and arranged in spaced relation with respect to said second terminal element, a disconnecting switch arranged in series relation with said arcing contacts and comprising a stationary disconnect contact and a cooperating movable disconnect contact, one of said disconnect contacts being in permanent conductive connection with said metal structure, and said movable disconnect contact normally extending across the space between said metal structure and said second terminal element, an actuating lever hinged to said movable disconnect contact, and a second fluid operated motor for operating said actuating lever for moving said movable disconnect contact to a lower level away from said stationary disconnect contact.

2. In a fluid blast circuit breaker the combination of a first fixed terminal element, a second fixed terminal element, a stationary arcing contact, a cooperating movable arcing contact, means for establishing a blast of fluid under pressure adjacent said arcing contacts, a first fluid operated motor for separating said arcing contacts, means for permanently conductively connecting one of said arcing contacts with said first terminal element, a fixed metal structure in permanent conductive connection with the other of said arcing contacts and arranged in spaced relation with respect to said second terminal element, a disconnect switch arranged in series relation with said arcing contacts and comprising a stationary disconnect contact and a cooperating movable disconnect contact hingedly supported by said metal structure and normally extending across the space between said metal structure and said second terminal element, and a second fluid operated motor for moving said movable disconnect contact to a lower level away from said stationary disconnect contact.

3. In a fluid blast circuit breaker the combination of a first terminal stud, a second terminal stud arranged parallel to said first stud, a pair of relatively movable arcing contacts, a fluid operated motor of the reciprocating type for separating said pair of arcing contacts, means for permanently conductively connecting one of said

arcing contacts with said first stud, metallic means defining a chamber in permanent conductive connection with the other of said arcing contacts and enclosing said arcing contacts, said chamber defining means being arranged in spaced relation with respect to said second stud and substantially coaxially with respect to said motor, a disconnecting switch arranged in series relation with said arcing contacts and operative upon separation thereof, said disconnecting switch being arranged substantially on one side of the common axis of said motor and chamber defining means and comprising a movable disconnect contact normally extending across the space between said chamber defining means and said second stud, said first stud, said arcing contacts, said disconnecting switch and said second stud defining a loop-shaped current path, a tank for storing fluid under pressure arranged outside of said loop-shaped current path on the side of said common axis of said motor and chamber defining means opposite said disconnecting switch, and means for establishing an arc extinguishing blast of fluid under pressure from said tank adjacent said arcing contacts.

4. In a fluid blast circuit breaker the combination of a first terminal stud, a second terminal stud arranged parallel to said first stud, a pair of relatively movable arcing contacts, a fluid operated motor of the reciprocatory type for separating said arcing contacts, means for permanently conductively connecting one of said arcing contacts with said first stud, metallic means defining a chamber in permanent conductive connection with the other of said arcing contacts and enclosing said arcing contacts, said chamber defining means being arranged in spaced relation with respect to said second stud and substantially coaxially with respect to said motor and parallel to the axes of said studs, a disconnecting switch arranged in series relation with said arcing contacts and operative upon separation thereof, said disconnecting switch being arranged substantially on one side of the common axis of said motor and chamber defining means and comprising a movable disconnect contact normally extending across the space between said chamber defining means and said second stud, said first stud, said arcing contacts, said disconnecting switch and said second stud defining a loop-shaped current path, a tank for storing fluid under pressure arranged outside of said loop-shaped current path on the side of said common axis of said motor and chamber defining means opposite said disconnecting switch, and means for establishing an arc extinguishing blast of fluid under pressure from said tank adjacent said arcing contacts.

5. In a fluid blast circuit breaker the combination of a pair of spaced parallel terminal studs, a pair of cooperating arcing contacts, a contact separating fluid operated motor of the reciprocatory type comprising a cylinder arranged substantially coaxially with respect to, and supported by, one of said studs, a chamber for enclosing said pair of contacts and arranged substantially coaxially with respect to said one of said pair of studs and supported by the cylinder of said mo-

tor, means for establishing a blast of fluid under pressure through said chamber in a direction generally away from, and longitudinally of, said one of said studs, and a disconnecting switch in series relation with said arcing contacts and operative upon separation thereof, said disconnecting switch comprising a hingedly supported contact normally arranged in acute angular relation to said studs and connecting one of said arcing contacts with the other of said studs.

6. In an electric switching device and combination of a fixed arcing contact and a cooperating movable arcing contact in series with a fixed disconnect contact and a cooperating movable disconnect contact, a lever means attached to said movable disconnect contact at a point intermediate the ends thereof, a first reciprocatory motor means actuated by fluid under pressure for actuating said movable arcing contact, and a second reciprocatory motor means actuated by fluid under pressure for actuating said lever means to move said movable disconnect contact in contact closing direction against the action of gravity and maintain the movable disconnect contact in engagement with said fixed disconnect contact against the action of gravity and for moving said movable contact in cooperation with the action of gravity for separating said disconnect contacts.

7. In a fluid blast circuit breaker the combination of a first fixed vertically mounted terminal element, a second fixed vertically mounted terminal element, a stationary arcing contact, a cooperating movable arcing contact, means for establishing a blast of fluid under pressure adjacent said arcing contacts, a first fluid operated motor for separating said arcing contacts, means for permanently conductively connecting one of said arcing contacts with said first terminal element, a fixed metal structure in permanent conductive connection with the other of said arcing contacts and arranged in spaced relation with respect to said second terminal element, a disconnecting switch arranged in series relation with said arcing contacts and comprising a stationary disconnect contact and a cooperating movable disconnect contact, said stationary disconnect contact being mounted at the lower end of said second terminal element and said movable disconnect contact being pivotally connected to said metal structure, said movable disconnect contact normally extending across the space between said metal structure and said second terminal element, and a second fluid operated motor connected with said movable disconnect contact for pivoting said movable disconnect contact downward to separate said disconnect contacts.
